CLAIM

The ornamental design for a micro automobile ramp, as shown and described.

DESCRIPTION

FIG. 1 is a side elevational view of the micro automobile ramp showing my new design, the opposite side view being a mirror image of that shown;
FIG. 2 is a frontal elevational view thereof;
FIG. 3 is a rear elevational view thereof;
FIG. 4 is a top plan view thereof;
FIG. 5 is a bottom plan view thereof; and,
FIG. 6 is a top perspective view thereof.
